SET OF BATH TREADS

Roger L. Dean, Geneva, Ill., assignor to Minnesota
Mining and Manufacturing Company, St. Paul, Minn.

Continuation-in-part of design application Ser. No.
173,732, Aug. 20, 1971. This application Feb. 7,
1972, Ser. No. 224,386

Term of patent 14 years

Int. Cl. D6—11

U.S. Cl. D6—210

FIG. 1

FIG. 3**FIG. 2**

FIG. 1 is a top plan view of a set of bath treads showing my design with the units of the set arranged in a position of use;

FIG. 2 is an end view taken from the left side of FIG. 1;

FIG. 3 is an end view taken from the bottom of FIG. 1.

This application is a continuation-in-part of copending application Ser. No. 173,732, filed Aug. 20, 1971.

I claim:

The ornamental design for the set of bath treads, substantially as shown and described.
